Elmer Brankinkey
ATTORNEY

UNITED STATES PATENT OFFICE.

SUSAN CLARE PEARSON, OF NEW YORK, N. Y.

SNAP FASTENER.

Application filed May 24, 1924. Serial No. 715,581.

To all whom it may concern:

Be it known that I, SUSAN CLARE PEARSON, a citizen of the United States, residing in Manhattan, in the city, county, and State of New York, have invented a new and useful Improvement in Snap Fasteners, of which the following is a specification.

My invention relates to snap fasteners of the press button type used principally on ladies' garments and has for its object the production of a device which will be durable and of economical construction, one which will be easily opened when it is desirable to open it.

15 In the construction of all the snap fasteners of which I am aware, two parts are used, a stud button and an engaging member formed out of metal in shape to receive the stud and to hold a spring which has substantially parallel sides for engaging the stud button. This spring may be of varying shapes but so far as I am aware they all engage two sides of the button which feature causes inefficient engaging means if any 20 pull is exerted in a direction perpendicular to the line of contact of these two points and the snap fastener easily opens, while if the pull is exerted in any other direction the fastener remains in engagement. To overcome this, many improvements have been made in the shape of the stud button and the engaging member so that the fastener will not pull open, with the result that it is quite difficult to open the two engaging 25 parts without putting one's finger nail in between the parts to pry them open. My improvement overcomes both these disadvantages common to the fasteners now on the market.

30 Referring to the accompanying one sheet of drawings, in which similar characters of reference indicate like parts throughout the several views,

Figure 1 is a top view of my fastener.

45 Figure 2 is a section on lines 2—2, Figure 1.

Figures 3, 4 and 5 are top views of modifications which I may employ.

In the carrying out of my invention I provide a stud button 1, provided with a base 2 and holes 3 by means of which the stud button may be attached to a garment. These

buttons are usually pressed out of metal and are common to fasteners of this type.

The engaging member is made of a spring 55 wire bent into a geometric form consisting of a corresponding number of spring arcs 5 and loops 6, the bow of the spring arcs curving in towards the center of the geometric figure. The ends of the wire may be joined as at 7 by any well known means or may be twisted as shown in Figures 3 and 4. It will be observed that in Figure 1 the spring arcs 5 contact on four sides of the stud while in Figure 5 the spring arcs 5 contact on three sides. When a particularly strong fastener is desired a small bend 8 in each of the spring arcs is made so that the contact points are more nearly in one plane where they engage with the stud, for it must 60 be observed that in tracing the geometric form the wire in crossing goes over and then under with regularity throughout.

In the manufacture of the device it may be found desirable to give a twist to the 75 loops 6 as at 9 and to do away with one loop and have the ends twisted as illustrated in Figure 4.

The loops 6 form a convenient means for securing the engaging member to a garment 80 but the main object of these loops which are of a size extending well over the base 2 of the stud button 1 is to provide a finger lift to open the fastener without the necessity of using the finger nail causing discomfiture 85 and breaking of the nail in many cases.

I wish it distinctly understood that my snap fastener herein described and illustrated is in the form in which I desire to construct it and that changes or variations may 90 be made as may be convenient or desirable without departing from the salient features of my invention and I therefore intend the following claims to cover such modifications as naturally fall within the lines of invention.

I claim:

1. A snap fastener comprising a stud button member, and a spring engaging member made of a single piece of wire bent into a plurality of spring engaging arcs and exterior twisted loops, all the loops being twisted in the same direction, and the said arcs bent transversely thereby presenting the spring

arcs to contact with the stud button so that the points of contact will fall in a single plane.

2. The device of claim 1 with the addition that the loops extend outside the base of the stud button.

3. The device of claim 1 with the addition that the wire in forming the spring arcs

crosses under and then over in regularity throughout. ¹⁰

In testimony whereof I affix my signature in the presence of two witnesses.

SUSAN CLARE PEARSON.
